United States Patent Office

Des. 186,679

Patented Nov. 17, 1959

186,679

BUTTER DISH

Richard Thomas Hopcraft, Warwick, R.I., assignor to
Gorham Manufacturing Company, Providence, R.I., a
company of Rhode Island

Application July 14, 1959, Serial No. 56,779

Term of patent 14 years

(Cl. D44—5)

Fig. 1

Fig. 2

Fig. 3

Fig. 4

Fig. 5

Figure 1 is a perspective view of a butter dish showing my new design;

Figure 2 is a top plan view of the cover;

Figure 3 is a top plan view of the base portion;

Figure 4 is a side elevational view partly in section of the assembled butter dish, and

Figure 5 is an end elevational view partly in section thereof.

I claim:

The ornamental design for a butter dish, as shown.
